No. 824,737.

PATENTED JULY 3, 1906.

F. O'DONNELL.
STOP MOTION FOR LOOMS.
APPLICATION FILED APR. 20, 1905.

UNITED STATES PATENT OFFICE.

FELIX O'DONNELL, OF PAWTUCKET, RHODE ISLAND, ASSIGNOR OF ONE-HALF TO SUSAN A. BROWN, OF PAWTUCKET, RHODE ISLAND.

STOP-MOTION FOR LOOMS.

No. 824,737.

Specification of Letters Patent.

Patented July 3, 1906.

Application filed April 20, 1905. Serial No. 256,602.

To all whom it may concern:

Be it known that I, FELIX O'DONNELL, a citizen of the United States, residing at the city of Pawtucket, in the county of Providence and State of Rhode Island, have invented certain new and useful Improvements in Stop-Motions for Looms, of which the following is a specification, reference being had therein to the accompanying drawings.

10 This invention relates to stop-motions for looms, and has for its object to provide means whereby the loom will be instantly stopped if for any reason the shuttle should fail to be thrown way across the loom, but should stop 15 on the lay and be carried thereby forward into the web.

In the ordinary loom if the shuttle should stop in the shed and be carried forward by the lay it would be jammed into the warp- 20 threads and break down all the threads it comes in contact with.

25 My invention consists, essentially, of means attached to the vibrator whereby said vibrator may be released and allowed to give way and at once relieve the tension on the whole warp, and at the same time the action of said vibrator in giving way operates mechanism to instantly and automatically stop the loom. Thus the breaking of the warp- 30 threads is effectually prevented.

Another feature of the device is that both of the temples are also connected up to the stop-lever, and should the shuttle stop opposite either of said temples said shuttle would 35 bring up against the same and through its mechanism connected to the stop-lever the loom would stop even before the vibrator-beam could operate.

In the ordinary loom sometimes the temple- 40 rolls become clogged and will not rotate. When this happens, the fabric becomes torn as it is drawn through them by the take-up-roll in front. By the use of my device the fabric cannot be torn in this manner, for should 45 the rolls become clogged the temples are drawn forward and by the mechanism attached thereto the loom is automatically stopped.

With these and other objects in view the 50 invention consists of certain novel features of

construction, as will be more fully described, and particularly pointed out in the appended claims.

In the accompanying drawings, Figure 1 is an end elevation of a portion of the loom-frame, showing some of the parts in section and illustrating the tripping device connected to the vibrator for stopping the loom when too great a tension is exerted on the warp-threads. Fig. 2 is a plan view of the stopping mechanism shown in Fig. 1. Fig. 3 is an enlarged perspective view of the vibrator-beam and the mechanism it actuates when drawn down by the warp-threads. Fig. 4 shows the spring-latch bolt which holds the vibrator-beam in position against the ordinary tension of the warp-threads. Fig. 5 is a plan view showing a portion of the breast-beam and temples with the shuttle in position to bring up against one of said temples 70 and stop the loom. Fig. 6 is an end elevation of the mechanism shown in Fig. 5.

Referring to the drawings, at 1 is a portion of the loom-frame, and 2 is the lay, which is represented as being on its forward stroke 75 carrying the shuttle 3, which shuttle has stopped thereon and is being jammed into the warp-threads.

At 4 is the usual breast-beam, and 5 the starting and stopping handle.

At 6 6 are the usual warp-threads that are led from the warp-beam 7 in the rear of the loom up over the vibrator-beam 8, over and under the lease-rods 9 and 10, through the harnesses 11 and 12 to the fell 13, where the weft-thread is laid in and beat up into a woven fabric. Connected to this vibrator-beam 8 is the downwardly-extending arm 14, in which arm is located the spring-actuated latch-bolt 15, (see Fig. 4), beveled at its outer end at 16. 90 This bolt engages a corresponding V-shaped notch 17 in a fixed plate 18 and is adapted to be readily withdrawn from said notch, allowing the vibrator to tip down and slacken the warp when an unusual strain is exerted on the said vibrator-beam by an excess tension on said warp. This plate is shown as extending around back of this arm at 23 and limits the forward motion of the vibrator. To this downwardly-extending arm 14 is con- 100

nected the forwardly-extending arm 19, in the outerend of which latter arm is a downwardly-extending adjustable contact-pin 20.

At 21 is a segment pivotally hung at 22, and 5 extending from the upper end of this segment is the adjusting or regulating handle 24. In the upper face of this segment is the notch 25, arranged to engage the tooth or corresponding projection 26 on the tripping-lever 10 27. This lever is pivoted at 28 and is acted on by the spring 29 to press the said tooth down into the said notch.

At 30 is the downwardly-extending arm that is connected to said segment, and at 31 15 is the rearwardly-extending ear that is acted upon by the spring 32 to throw said arm 30 backward when the tooth 26 is disengaged from its notch 25, and through the connection 33, lever 34, and arm 35 the stopping-lever 5 is disengaged from its notch and 20 instantly flies back and the loom is stopped.

At 35^a 35^a in Fig. 5 are the two ordinary spring-actuated temples that extend inward from the breast-beam 36. Pins or lugs 37 37 25 project out laterally from each of said temples to engage the levers 38 38, which levers are mounted on and keyed to the shaft 39. These pins or lugs are normally held a short 30 distance away from the lever 38, so as to permit a slight movement of the shank of the temple at the time of the beating up of the cloth without coming in contact with said lever. When the shuttle 3 remains in the 35 shed, is carried forward and comes in contact with one of these temples, said temple is driven back and through the lever 38, shaft 39, lever 34, that is also keyed to said shaft 39, and lever 35 the shipper-lever 5 is thrown off and the loom instantly stopped without 40 doing damage to the fabric or breaking the threads. Another feature of this stopping mechanism connected to the temple is that if for any reason the temple-roll becomes clogged and will not rotate and the take-up 45 roll exerts a tension on the temple sufficient to draw the same forward the stopping mechanism will be actuated to stop the loom before this strain is sufficient to tear the fabric.

50 The operation of the invention may be further described as follows: My invention is a simple and practical device that may be readily attached to any loom with but small expense, and by its use the loom is stopped 55 automatically, and it will be impossible to break a warp-thread by the stopping of the shuttle in the web. By the use of my device when the shuttle stops in the shed and is carried forward by the lay the tension on the 60 warp-threads is greatly increased; but before that tension reaches the breaking-point in the yarn the pull on the upper edge of the vibrator-beam causes the latch-bolt 15 to be

withdrawn from its notch 17 and allows said vibrator to swing forward, thereby instantly, 65 slackening up the yarn, and at the same time the forward movement of the vibrator acting through the arms 14 and 19 the pin 20 presses on the lever 27, withdrawing the tooth 26 from the notch 25, and allows the spring 32 to 70 act, which spring, acting through the arm 30, connecting-rod 33, levers 34 and 35, releases the stopping-lever 5 and the loom is stopped.

Having thus described my invention, what I claim as new, and desire to secure by Letters Patent, is—

1. In a stop-motion for looms, the combination of the shuttle, the lay, and the temples, and means whereby the loom will be stopped automatically if for any cause the 80 temples are drawn inward.

2. In a stop-motion for looms, the combination of the shuttle, the lay, and the temples, and means whereby the loom will be stopped^a automatically to prevent breaking 85 down the warp-threads when the shuttle stops in the shed and is carried forward by the lay against either of said temples.

3. In a stop-motion for looms, the combination of the shuttle, the lay, and the vibrator, means whereby the vibrator-beam will 90 yield when an excess tension is exerted on the warp-threads and spring-actuated means released by the movement of the vibrator to stop the loom.

4. In a stop-motion for looms, the combination of the shuttle, the lay, and the vibrator, means in said vibrator arranged to hold it normally against the ordinary tension of the warp-threads, and means whereby said 100 vibrator may be allowed to yield when an excess tension is exerted on the same, and means whereby the movement of said vibrator operates mechanism to stop the loom.

5. In a stop-motion for looms, the combination of the shuttle, the lay and the vibrator, a spring-actuated latch-bolt arranged to normally hold said vibrator in a given position against the ordinary tension of the warp-threads upon it, and means whereby said bolt 110 is operated automatically to release said vibrator and slacken the warp when an excess-ive strain is brought to bear upon the same and thereby prevent the warp from breaking.

6. In a stop-motion for looms, the combination of the shuttle, the lay, and vibrator, a spring-actuated latch-bolt arranged to normally hold said vibrator in a given position against the ordinary tension of the warp-thread upon it, and means whereby said bolt 120 is operated automatically to release said vibrator and slacken the warp when an excess-ive strain is brought to bear upon the same, and means whereby the movement of the vi-brator when released operates to stop the 125 loom and prevent the warp from breaking.

7. In a stop-motion for looms, the combination of the shuttle, the lay, a vibrator pivotally hung from the loom-frames, a spring-actuated latch-bolt arranged to normally hold said vibrator in a given position against the ordinary tension of the warp-threads upon it, means whereby said bolt may be withdrawn automatically and allow said vibrator to tip down and release the warp when

an excess tension is applied to the same, and means whereby the tipping down of said vibrator operates mechanism to stop the loom.

In testimony whereof I affix my signature in presence of two witnesses.

FELIX O'DONNELL.
